US0D1005044S

(12) **United States Design Patent** (10) **Patent No.:** **US D1,005,044 S**
(45) **Date of Patent:** **** Nov. 21, 2023**

(54) **DRINKING CUP**

(71) Applicant: **Taizhou Kunhai Plastic Industry Co., Ltd.**, Zhejiang (CN)

(72) Inventor: **Shangjiang Gu**, Zhejiang (CN)

(73) Assignee: **Taizhou Kunhai Plastic Industry Co., Ltd.**, Zhejiang (CN)

(**) Term: **15 Years**

(21) Appl. No.: **29/888,757**

(22) Filed: **Apr. 4, 2023**

(30) **Foreign Application Priority Data**

Dec. 9, 2022 (EM) 015005782-0001

(51) **LOC (14) Cl.** **07-01**

(52) **U.S. Cl.**

USPC **D7/510**; D24/197

(57) **CLAIM**

The ornamental design for a drinking cup, as shown and described.

DESCRIPTION

FIG. 1 is a front, right and top perspective view of a drinking cup, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of my new design for a drinking cup, shown in a closed configuration.

The broken lines depict portions of the drinking cup that form no part of the claimed design.

1 Claim, 9 Drawing Sheets
